INVENTOR:

Charles A. Bailey.

BY
Arthur B. Jenkins
ATTORNEY.

UNITED STATES PATENT OFFICE.

CHARLES A. BAILEY, OF CROMWELL, CONNECTICUT.

VIBRATING SHELL.

1,401,859.

Specification of Letters Patent. Patented Dec. 27, 1921.

Application filed September 4, 1920. Serial No. 408,240.

To all whom it may concern:

Be it known that I, CHARLES A. BAILEY, a citizen of the United States, and a resident of Cromwell, in the county of Middlesex and State of Connecticut, have invented 5 new and Improved Vibrating Shells, of which the following is a specification.

My invention relates to the class of devices employed to produce sound, more especially as a source of amusement, and an 10 object of my invention, among others, is to provide a device of this class that shall be extremely simple in construction and that shall produce a more or less pleasing sound 15 and one that can be made at a minimum expense.

Forms of devices embodying my invention and in the construction and use of which the objects herein set out, as well as others, 20 may be attained, are illustrated in the accompanying drawings, in which—

Figure 1 is a side view of one form of my improved sounding device.

Fig. 2 is a view in cross section through 25 the same.

Fig. 3 is a top edge view.

Fig. 4 is a perspective view of a little different form of sounding device embodying my invention.

Fig. 5 is a perspective view of still another 30 form, with parts broken away to show construction.

My improved vibrating shell embodies a structure that is formed from a single piece 35 of sheet metal with sides bent up into a more or less U-shape, and with ends and a front edge bent inwardly toward each other from the sides, in the form of the device illustrated in Figs. 1 to 3 the numeral 7 in- 40 dicating the back of my improved vibrating shell that is preferably narrow, as compared with the sides 8, which sides are bent at substantially right angles to the back and in more or less parallel relation one to the 45 other, each of said sides having ends 9 bent at substantially right angles to the sides and lying in substantially the same plane and with their edges quite close together. Flanges 10 are also bent inwardly from the 50 sides and toward each other, said ends and flanges being arranged to provide end slots 11 and a front edge slot 12, and in order to produce more or less musical sounds open- 55 ings 13 and 14 are formed in the back and side respectively with slots 15—16 extending from said openings, the former into cross-

wise slots 17 formed between the ends of the back 7 and the ends 9, and the latter extending into slots 18 formed between the in-turned ends and the sides, as shown in 60 Figs. 1 to 3 of the drawings.

In order to further increase or vary the musical sounds extra slots 19 are cut into one or both sides, preferably one side, and a bulbous enlargement 20 may be formed on 65 one or both sides for the same purpose. Tongues 21 may also be formed at the edges of the flanges 10 projecting inwardly into the space within the shell for the purpose of partially obstructing the movements of 70 a striker 22 of any desired shape loosely enclosed within the case. A handle 23 may be attached to the shell in any desired manner as a means for shaking it to produce 75 sounds therefrom.

The device illustrated in Fig. 4 is much the same as that just described except as to shape, the device of Fig. 4 being somewhat cubical in form but having the back 24, sides 25, inturned ends 26 and inturned 80 front edge 27 and also having holes and slots as hereinabove set forth.

In the form of the device illustrated in Fig. 5 the shell itself embodies a handle 28 extending from a shell body 29, the whole 85 being of more or less U-shape as described with respect to the other devices, this structure having bent-up sides, inturned ends and inturned front edge with the slots between the back, sides, ends and front edge 90 as hereinbefore described. In this latter form of the device the striker 31 is mounted on a pivot 32 extending between the side parts, as clearly shown in the drawings.

I claim—

1. A sound producing device comprising a shell formed from a single piece of sheet metal of substantially U-shape in cross section, with upturned sides, inturned ends, and a flanged front edge forming an angularly 100 shaped structure in all directions, and a striker loosely inclosed within the shell.

2. A sound producing device comprising a shell formed from a single piece of sheet metal of substantially U-shape, with up-turned sides, inturned ends, and a flanged front edge forming an angularly shaped structure in all directions, with slots between the back and the sides, and a striker 105 loosely inclosed within the shell.

3. A sound producing device comprising a shell formed from a single piece of sheet

metal of substantially U-shape, with upturned sides, inturned ends, and a flanged front edge forming an angularly shaped structure in all directions, with slots between the back and ends, and a striker loosely inclosed within the shell.

4. A sound producing device comprising a shell formed from a single piece of sheet metal of substantially U-shape, with upturned sides, inturned ends, and a flanged front edge forming an angularly shaped structure in all directions, with slots between the ends and sides, and a striker loosely inclosed within the shell.

10 5. A sound producing device comprising a shell formed from a single piece of sheet metal of substantially U-shape, with upturned sides, inturned ends, and a flanged front edge forming an angularly shaped structure in all directions, and with openings and with slots extending from the openings into slots in the bounding walls of the shell, and a striker loosely inclosed within the shell.

20 6. A sound producing device comprising a shell formed from a single piece of sheet metal of substantially U-shape, with upturned sides having a bulbous projection thereon, said shell also having inturned ends and a flanged front edge, and a striker loosely inclosed with the shell.

25 7. A sound producing device comprising

a shell formed from a single piece of sheet metal of substantially U-shape in cross section, with upturned sides, inturned ends, and a flanged front edge forming an angularly shaped structure in all directions, with a space between the edges of the ends and between the flanges of the front edge, and a striker loosely inclosed within the shell.

30 8. A sound producing device comprising a shell formed from a single piece of sheet metal and including a back, sides extending at an angle to the back from opposite edges thereof, ends extending at an angle to and from each of the sides, and flanges bent at an angle to and from each of the sides and constituting the front walls of the shell.

35 9. A sound producing device comprising a shell of substantially angular shape and including a back forming one edge of said shell, a set of oppositely disposed side members and a set of oppositely disposed end members all formed from a single piece of sheet metal, each of the side members and each of the end members being bent at an angle to the piece which supports them, said sides and ends forming four sides of the shell, and flanges bent at an angle to and 40 integral with the members of one of said sets and comprising the remaining wall of said shell.

45 CHARLES A. BAILEY.
